UNITED STATES PATENT OFFICE.

OSCAR F. FORSBERG, OF YONKERS, NEW YORK, ASSIGNOR TO WESTERN ELECTRIC COMPANY, OF NEW YORK, N. Y., A CORPORATION OF ILLINOIS.

CASH-RECEPΤΑCLE FOR COIN-COLLECTORS.

1,104,042.

Specification of Letters Patent. Patented July 21, 1914.

Application filed June 1, 1912. Serial No. 700,965.

To all whom it may concern:

Be it known that I, OSCAR F. FORSBERG, citizen of the United States, residing at Yonkers, in the county of Westchester and State of New York, have invented a certain new and useful Improvement in Cash-Receptacles for Coin-Collectors, of which the following is a full, clear, concise, and exact description.

This invention relates to improvements in cash boxes, and has for its object to provide means for automatically closing the opening for the receipt of coins when the cash box is removed from its casing or receptacle, and for locking the mechanism in this position to prevent the unauthorized removal of coins therefrom.

This invention is designed primarily for use with coin collectors for telephone systems, but is not limited exclusively to such use.

In the preferred form of the invention, the cash box is provided with an opening in its top, beneath the coin deposit chute, for the receipt of coins. A pivoted closure is arranged to be placed in front of the opening when the cash box is removed from its casing or receptacle, and to be removed from in front of the opening when the cash box is in place. Means are provided for locking the cash box in the receptacle until the closure covers the coin-receiving opening, at which time the cash box may be removed. A locking device is also provided which prevents the coin-receiving opening from being inadvertently closed before the cash box is placed in position in the receptacle.

In the drawings illustrating this invention—Figure 1 is a perspective view of the cash box in position, parts of the receptacle being broken away, and the door thereof being open; Figs 2, 3 and 4 are views of the mechanism in the top of the cash box, showing respectively, the relations of the parts when the closure is locked in an intermediate position, completely removed from the coin-receiving opening, and in a position to unlock the cash box from the receptacle; Fig. 5 is a view of a part of the frame supporting the cash box.

Referring to the drawings, 1 designates the receptacle for containing the cash box, 2 is a door therefor, and 3 is the cash box. The cash box is supported within the receptacle by a frame 4, securely mounted upon

the receptacle, engaging with the cover 5 of the cash box. Within the cover 5 are located the locking and closing mechanisms, consisting of a closure 6, pivotally supported at 7 and having pinion teeth 8, meshing with the rack teeth 9 of a sliding member 10. The relation of the closure 6 and the sliding member 10 is such that when the sliding member is in its rearmost position, the closure 6 is removed from in front of a coin-receiving opening 11, and when the sliding member 10 is in its extreme forward position the closure 6 is placed in front of the coin-receiving opening 11.

The sliding member 10 is provided with a downwardly projecting lug 12 arranged to be engaged by the tumblers 13 of a lock 14, which may be of any suitable form. The sliding member 10 is also provided with a hooked lug 15 arranged to lock with a lug 16 of a sliding member 17, and thus prevent the further withdrawal of the sliding member 10, except in the manner hereinafter described.

The sliding member 17 is provided with a lug 18 which locks the cash box to the frame 4 by entering a projection 19 through an opening 20 in the frame 4, but which may be withdrawn from said opening as hereinafter described for releasing the cash box from the frame 4. The sliding member 17 is further provided with lugs 21 and 22 between which is located the free end of a spring member 23 secured at the points 24 and 25. When the cover of the cash box is inserted in the frame 4, the lug 18 engages the side of the frame and pushes the sliding member 17 against the tension of the spring 23 to take such a position that the lug 15 may move past the lug 16 without being engaged thereby. With the cash box in its normal position in the receptacle, a ledge 26 of the lug 18 engages the edge of an opening 20 in the frame 4 and holds the lug 16 out of the path of the hooked lug 15 of the sliding member 10. In this condition the sliding member 10 may be withdrawn to close the opening 11 by means of the closure 6. A lug 27, also forming part of the sliding member 17, is located in a position to be struck by the closure 6 to withdraw the lug 18 from the opening 20 against the pressure of the spring member 23, and thus release the cash box from the frame so that it may be withdrawn from the receptacle.

The member 10 is withdrawn until the tumblers 13 of the lock 14 drop behind the downwardly projecting lug 12, thus securely locking the mechanism until it is released by the proper key being inserted in the lock 14.

The door 2 is equipped with a projecting lug 28 so situated that upon the closing of the door 2 the lug 28 contacts with a downwardly projecting part of the sliding member 16, forcing it to its extreme rear position (thus causing the closure 6 to be removed from in front of the opening 11).

The lug 15 of the sliding member 10 and the lug 27 of the sliding member 17 are so constructed and located with respect to each other that just before the door 2 is completely closed the lug 15 engages the beveled portion of the lug 27 moving the sliding member 17 to cause the lug 18 to enter the opening 20. Thus the locking of the cash box to the receptacle is insured even though the tension of the spring 23 fails to move the sliding member 17 to accomplish this result. This arrangement of lugs 15 and 27 secures a further safeguard against the heating of the device, since the sliding member 17 cannot be wedged or otherwise secured in such a position that the lug 18 is outside of the opening 20 and still allow the complete removal of the closure 6 from the opening 11 and the closing of the door 2. From the position of the mechanism shown by the dotted lines of Figs. 2 and 4, it will be noted that when the lug 18 is in a position to release the cash box the sliding member 17 is moved inward sufficiently to cause the lug 27 to take a position behind the lug 15 of the sliding member 10. The sliding member 10 being forced in will cause the lug 15 to contact with the beveled portion of the lug 27 forcing the sliding member 17 to cause the lug 18 to enter the opening 20. If by any means the sliding member 17 is prevented from moving, the contact between 15 and 27 will prevent the further inward movement of sliding member 10. In this condition the closure 6 will partially obstruct the opening 11 and on account of the lug 28 it will be impossible to close the door 2.

The operation of the apparatus is as follows:—Upon wishing to remove the cash box the door 2 is unlocked and opened. The projecting portion of the sliding member 10 is then given a pull forward, which movement of the sliding member 10 rotates the closure 6 about the pivot 7 through the agency of the rack and pinion 8, 9, causing the closure 6 to move across the opening 11. The sliding member 17 is held by the engagement of the ledge 26 of the lug 18 with the edge of the opening 20 in such a position that the hooked lugs 15 and 16 do not lock. In rotating about its pivot 7, the closure 6 strikes the lug 27, forcing the bar 17

to withdraw the lug 18 entirely out of the opening 20. This withdrawal of the lug 18 unlocks the cash box from the frame 4, and a further pull on the projecting part of the sliding member 10 removes the cash box 70 from the receptacle. As the closure 6 starts to remove the lug 18 from the opening 20, the downwardly projecting lug 12 of the sliding member 10 passes the projections of the tumblers 13 of the lock 14, which dropping into place behind the lug 12 prevent the return of the sliding member 10 and the withdrawal of the closure 6. Therefore upon being released from the frame 4, the cash box is securely closed and locked. The proper key being inserted in the lock 14, the tumblers 13 may be rotated so that the projecting lug 12 is released, allowing the inward movement of the member 10 to cause the closure 6 to be withdrawn from the opening 11 through the agency of the rack and pinion teeth 8, 9. The contents of the cash box may then be removed through the opening 11. To replace the cash box, the key inserted in lock 14 is turned to release 90 the tumblers 13, which, however, are unable to drop into the locking position behind the projecting lug 12, since the spring member 23 has forced the sliding member 17 into such a position that the hooked lugs 15 and 95 16 allow only a limited amount of movement of the sliding member 10. This prevents the accidental closing of the coin-receiving opening and locking of the mechanism before the cash box is in position in the receptacle. When the cover 5 of the cash box is inserted in the frame 4, the projecting lug 18 is forced in to such an extent that the lugs 15 and 16 cannot contact with each other. When the cash box is placed in its 105 normal position in the frame 4, the lug 18 is opposite the opening 20 which allows the spring 23 to move the sliding member 17 outward to such a position that the ledge 26 contacts with the edge of the opening 20. 110 The sliding member 17 moves so that the lug 18 still projects through the opening 20 into the projection 19 sufficiently to lock the cash box to the frame, but not far enough to allow the interlocking of lugs 15 and 16. 115 The closing of the door 2 causes the lug 28 to contact with the projecting end of the sliding member 10, moving it to its extreme rear position and removing the closure 6 entirely from the opening 11. The cash box 120 in this position is ready to receive coins dropped into it through the opening 11.

What I claim is:

1. The combination with a receptacle and a door therefor, of a cash box adapted to be 125 inserted therein having a coin receiving opening, a closure therefor, means self-acting upon the insertion of said box for locking said box within said receptacle, and means for moving said closure to open and 130

closed position and through the instrumentality of said closure unlocking said box from said receptacle.

2. In combination with a receptacle, a cash box adapted to be inserted therein having an opening for receiving coins, a closure therefor, means for actuating said closure, locking means for arresting said actuating means in an intermediate position, and means operable by said receptacle for unlocking said locking means.

3. In combination with a receptacle, a frame, a cash box attachable to said frame and having a coin receiving opening therein, a closure therefor, means for actuating said closure, means for arresting said actuating means in an intermediate position, a lock for retaining said closure in closed position, and means operable by said frame for actuating said arresting means.

4. In combination with a receptacle and a door therefor, of a frame, a cash box attachable to said frame and having a coin-receiving opening therein, means for locking said cash box to said frame, a closure for said opening, a lock for retaining said closure in closed position, means operable by said door for actuating said closure, and means operable by said closure for unlocking said cash box from said frame.

5. In combination with a receptacle and a door therefor, of a frame, a cash box attachable to said frame and having a coin-receiving opening therein, a closure for said coin-receiving opening, means for locking said cash box to said frame, means by which said cash box may be removed from said frame and operating said closure, a lock for retaining said closure in closed position, and means operated by said closure for unlocking said cash box from said frame.

6. In combination with a receptacle and a door therefor, of a cash box adapted to be inserted therein having an opening for receiving coins, a pivoted closure therefor, a sliding member for actuating said closure, locking means for arresting said sliding member in an intermediate position, and a second sliding member operable by said receptacle for unlocking said locking means.

7. In combination with a receptacle and a door therefor, of a cash box adapted to be inserted therein having a coin-receiving opening, a pivoted closure therefor, means actuated by the insertion of said cash box for locking said box within said receptacle, a sliding member operable by said door for removing said pivoted closure from said coin-receiving opening and operable to move said pivoted closure to closed position, a lock for arresting said closure in closed position, and a second sliding member operable by said pivoted closure for actuating said first mentioned locking means.

8. In combination with a receptacle, a cash box having a cover with an opening therein, a locking device mounted in said cover and adapted to coöperate with said receptacle, a closure for said opening adapted when in closed position to hold said locking device in unlocked position, means for operating said closure, and a lock for retaining said closure in closed position.

9. In combination with a receptacle, a cash box having a cover with an opening therein, a locking device mounted in said cover and adapted to coöperate with said receptacle, a closure for said opening adapted when in closed position to hold said locking device in unlocked position, means for operating said closure, an interlocking connection between said locking device and said last mentioned means for preventing the closing of said closure when the cash box is not in said receptacle, and a lock for retaining said closure in closed position.

10. In combination with a receptacle, a cash box adapted to be inserted therein, having an opening for receiving coins; a sliding member provided with rack teeth, a downwardly projecting lug, and a hooked lug; a lock for engaging said downwardly projecting lug; a pivoted closure for said coin receiving opening having pinion teeth for engaging with said rack teeth; a second sliding member; a lug thereon for engaging with the hooked lug on said first mentioned sliding member; a spring; lugs on said second mentioned sliding member for engaging said spring; a locking device for engaging with said receptacle; and a lug on said second mentioned sliding member arranged to be struck by said pivoted closure for unlocking said locking device and to coöperate with said hooked lug for locking said locking device.

11. In combination with a receptacle and a door therefor, of a frame, a cash box attachable to said frame and having a coin receiving opening therein, a sliding member having rack teeth thereon and a hooked lug, a closure for said coin receiving opening equipped with pinion teeth for engaging said rack teeth, a lock for retaining said closure in closed position, a second sliding member, a lug thereon for engaging the hooked lug on said first mentioned sliding member to limit its movement, and a second lug contacting with said frame for actuating said second mentioned sliding member.

12. In combination with a receptacle and a door therefor, of a frame having an opening therein, a cash box attachable thereto and having a coin receiving opening therein, a pivoted closure for said opening equipped with pinion teeth, a sliding member having rack teeth for engaging said pinion teeth to actuate said pivoted closure, a lock for retaining said closure in closed position, a

hooked lug on said sliding member, a second sliding member, a lug thereon arranged to contact with said first mentioned hooked lug for limiting the movement of said first mentioned sliding member, a spring tending to move said second mentioned sliding member, a second lug on said second mentioned sliding member for entering the opening in said frame, and a third lug on 10 said second mentioned sliding member arranged to be actuated by said pivoted closure to withdraw said second lug from said

opening and arranged to contact with the hooked lug on said first mentioned sliding member to cause the second lug on said second mentioned sliding member to enter the opening in said frame. 15

In witness whereof, I, hereunto subscribe my name this 29th day of May, A. D. 1912.
